CLAIM

The ornamental design for a trailer, as shown and described.

DESCRIPTION

FIG. 1 is a perspective view of the trailer of the present invention;

FIG. 2 is a front view thereof;

FIG. 3 is a rear view thereof;

FIG. 4 is a top view thereof;

FIG. 5 is a bottom view thereof; and,

FIG. 6 is a right side view thereof, the left side view being a mirror image of the right side.

The broken lines shown in FIGS. 3, 5 and 6 are for illustrative purposes only and form no part of the claimed design.
